UNITED STATES PATENT OFFICE.

CARLIND E. MYERS, OF CAMDEN, NEW JERSEY.

SEWING-MACHINE.

1,314,891.

Specification of Letters Patent.

Patented Sept. 2, 1919.

Application filed January 18, 1916. Serial No. 72,657.

To all whom it may concern:

Be it known that I, CARLIND E. MYERS, a citizen of the United States, and resident of Camden, county of Camden, and State of New Jersey, have invented an Improvement 5 in Sewing-Machines, of which the following is a specification.

The object of my invention is to provide certain improvements in the construction of 10 high speed sewing machines, more particularly for making zig-zag or over-seaming stitches, which shall be capable of great efficiency and durability.

My invention is more particularly intended for the "Wheeler & Wilson" type of sewing machine as made for commercial manufacturing with a special object of eliminating, as far as possible, reciprocating jointed parts and substituting means involving 15 rotary action for the purpose of eliminating lost motion, objectionable wear and looseness, back-lashing, and imperfect lubrication. My object is also to eliminate as far as possible causes of objectionable 20 noise with the object of producing a sewing machine which may be run at enormous speeds and with comparatively noiseless action.

By my improvements applied to sewing 25 machines, I am enabled to run the machines in commercial usage at a speed of upward of 3000 revolutions per minute with materially less wear and tear and less noise than the ordinary commercial machines when 30 running at approximately one-half the speed.

With the above and other objects in view, the nature of which will be more fully understood from the description hereinafter, the invention consists in the novel construction 35 of sewing machine as hereinafter more fully described and defined in the claims.

Referring to the drawings:—Figure 1 is a side elevation of a sewing machine embodying my improvements with a portion 40 broken away and certain parts removed to more fully disclose the construction; Fig. 2 is a view looking upward upon the bottom of the machine; Fig. 3 is a cross section through the bed of the machine and operative parts on line $x-x$ of Fig. 2; Fig. 4 is a similar view on line $y-y$ of Fig. 2; Fig. 5 is a cross sectional view on line $z-z$ of Fig. 1; Fig. 6 is a sectional view of the crank head for operating the needle bar; Fig. 7 is a perspective view of one of the 45 bearings removed; Fig. 8 is a sectional ele-

vation illustrating the cloth feed mechanism; Fig. 9 is a detail with part broken away for operating the cloth feed mechanism; Fig. 10 is a plan view with part of 50 the casing in section showing the manner of operating the cam which oscillates the needle; Fig. 11 shows a modification of the manner of driving the two main shafts of 55 the sewing machine; and Fig. 12 is a section of a detail of the bar which operates the needle holder.

2 is the bed and 3 the over-hanging arm of the sewing machine which may be made of the usual general construction common 60 to sewing machines. Arranged in the over-hanging arm and in suitable bearings therein as customary, is a straight horizontal driving shaft 4 which may be driven by a band from the usual band wheel. At the 65 over-hanging end of the arm, the needle bar 7 is arranged and adapted to reciprocate vertically as is customary, and this is reciprocated by means of a crank pin 6 on a crank head 5 secured to the end of the shaft 70 4. The crank pin 6 of the crank head may connect with the needle bar 7 by the usual pitman or link, the particular manner of applying the power to the needle bar being immaterial. The crank head 5 is best shown 75 in Fig. 6 from which it will be seen that the end opposite to the crank pin is provided with gear teeth 5^a, and the metal immediately back of the crank pin and between it and the gear portion is cut away as at 5^b 80 so that the heavy metal at 5^c on the opposite side of the body acts as a counterweight 85 to counterbalance the weight of the reciprocating needle bar and its connections when the machine is being run at a high speed. 90 As the crank head revolves at a speed as high as 3000 revolutions per minute, the centrifugal action of this counterweight portion 5^c acts in an effective manner in 95 overcoming the gravity action of the needle bar and its connections and steadies the operation 100 of the mechanism, giving to it a very positive action.

26 is a rotary take-up and is secured upon a shaft 26^a carried in a bearing in frame 27 105 secured to the top of the overhanging arm, and this shaft 26^a is provided with a gear 26^b which meshes with the gear 5^a of the crank head, as will be understood from Figs. 1 and 5. In this manner, the rotary action 110 of shaft 4 and crank head produces a rotary action to the take-up device, and as this is

devoid of reciprocating parts it is manifest that the speed may be run at 3000 revolutions per minute without injury to the structure. I do not restrict myself to any special 5 form of a take-up device, as any rotary take-up suitable for a sewing machine may be employed so long as it is driven in the manner herein shown and described.

The needle bar 7 is provided with an oscillating needle holder 16 pivoted to the needle bar at 16^a, and said holder is provided with an upwardly extending rod or arm 16^c by which it may be oscillated. By oscillating the needle holder, the needle may be made 10 to vibrate at its pointed end, while at the same time having the vertical reciprocatory motion through the needle bar, such as is required for zig-zag or over-seaming stitching, all of which is well known and does not 15 constitute any special feature of my invention. Heretofore, it has been customary to oscillate the needle holder by means of certain hinged mechanism which had a tendency under reasonable speeds to wear and 20 become loose and unreliable, and to overcome these defects I have employed the particular mechanism illustrated and to which reference will now be made. 21 is the usual cam for operating the needle holder, and is 25 driven by means of a bevel gearing 22 (Fig. 10) by which the cam 21 receives rotary motion directly from the shaft 4. The cam wheel 21 oscillates a pivoted arm 33. A bar 30 17 connects at one end with the arm 16^c of the needle holder, and at the other end with the pivoted arm 23 through a pin 23^a adjustable upon the arm 23 to vary the throw. 35 At the opposite end of the bar 17 there is pivoted at 19^a a hub portion 19 having a vertical hole through which the rod or arm 16^c of the needle holder loosely extends, and 40 by which it may be oscillated by the reciprocations of the bar 17. The bar adjacent to this end is provided with a guide slot 18 in 45 which is arranged a guide block 18^a pivoted at 18^b to a casting 20 bolted to the side of the over-hanging arm 3. In this manner, the bar 17 may be guided while being reciprocated, the said guide block being capable of 50 oscillatory motion to accommodate itself to any oscillation of the bar thereon due to the action of the pivoted arm 23. The bar 17 may be adjusted longitudinally to vary its length, and provision is made therefor by 55 forming the end 24 which connects with the hinged arm 23 as a separate piece and provided with a longitudinal slot 24^c through which clamping screws 24^a extend and engage the bar 17 to hold it in adjusted position. 60 A plate 24^b may be arranged under the heads of the screws 24^a so as to provide a better clamping action upon the plate 24 and hold it in its adjustment upon the bar 17 more positively. This adjustable arrangement of the bar is best shown in Figs. 1 and

12. Any other suitable manner of adjusting the length of the bar 17 may be employed in lieu of that shown. Provision for this adjustment is desirable because when the bar 17 is adjusted up or down upon the arm 23 to 70 vary the throw, it swings about the axis 18^b and would tend to throw the needle point out of position, and to avoid this some means of ready adjustment should be employed. The means shown is only by way of example, 75 however, and may be varied. A spring 25 is employed to maintain the free end of the arm 23 in contact with the inner wall of the cam groove of cam wheel 21, one end of said spring being connected with the bar 17 and 80 the other end with the frame of the over-hanging arm 3. By employment of this spring 25, more accurate action of the cam is insured, and any lost motion due to wear is overcome since the arm 23 is made to 85 constantly bear against one continuous surface or wall of the cam groove.

It will be understood from the foregoing description that as the shaft 4 rotates, the cam wheel 21 is likewise rotated in a continuous 90 manner, but by reason of the bevel gearing 22 being of the construction shown in Fig. 10, the speed of the cam wheel 21 is one-half that of the shaft 4 and the cam is such that the needle is oscillated into its extreme 95 positions alternately with the vertical reciprocations of the needle bar. As the arm 23 is oscillated by the cam, the bar 17 is reciprocated upon the block 18^a, and by this action and through the pivoted hub 19, it oscillates 100 the needle holder 16. The guide block 18^a is relatively large and forms an excellent guide for the free end of the bar 17 which will permit a very high speed without undue wear. Furthermore, the moving mass at the end of 105 the bar is reduced to a minimum and therefore the inertia to be overcome in the reciprocations is likewise reduced and permits a rapid speed with minimum wear and lost motion.

At the bottom of the machine the cloth feed mechanism, as well as the shuttle mechanism, are suitably driven by a continually rotating shaft 8 journaled in the frame of the machine in any suitable manner. This 110 shaft 8 similarly to the shaft 4 is a continuous straight shaft and hence may be rotated at a very high speed without introducing difficulties by centrifugal action, as occurs in those types of machines where cranks are 115 employed in the upper and lower shafts for the transmission of motion by means of links. Motion is transmitted from the upper shaft 4 to the lower or driven shaft 8 by suitable power transmitting devices which travel 120 in a continuous direction and are devoid of reciprocating motion, and the preferred mechanism for this purpose is more fully 125 illustrated in Figs. 1, 2 and 7. 9 is a vertical shaft extending almost for the full distance 130

between the shafts 4 and 8, and is arranged in the vertical portion of the over-hanging arm 3. The upper end of the shaft 9 is connected with the driving shaft 4 by miter gears 10, and the lower end of the said shaft 9 is connected with the driven shaft 8 by means of miter gears 11. It will be observed that these miter gears 10 and 11 are so arranged that the connection with the shaft 4 and the shaft 8 is at opposite sides of the shaft 9, this being to insure the rotation of the driven shaft 8 in the same direction as the driving shaft 4, but while this is essential in the particular mechanism shown in the present application, it is manifest that the shaft 8 might be rotated in the reverse direction to Fig. 4 if the shuttle and feeding mechanisms were suitably designed to permit such reversal movement, and I therefore do not restrict myself to the rotation of the shafts 4 and 8 to be in the same direction. Furthermore, I do not restrict myself to the gears 10 and 11 being miter gears, as it is manifest that they might be bevel gears of suitable dimensions so long as the speeds of the shafts 4 and 8 are the same, as the particular speed of shaft 9 is not material. The shaft 9 is journaled in a suitable casting 12 having top and bottom bearing portions 13. This casting 12 is provided with laterally extending hubs 13^a which project through the side of the vertical portion of the over-hanging arm and are screwed tightly to plates 14 by means of screws 15. These plates 14 are set into planed recesses 3^a in the side of the over-hanging arm portion, and are secured therein by screws 14^a. In this manner the bearing casting 12 may be arranged within the hollow chamber of the over-hanging arm, and may be accurately adjusted as to position by means of the particular attachment shown, and moreover may be readily removed for repairs when necessary.

45 28 is the feed bar and is provided with the usual serrated feed jaw or plate 28^a. This bar 28 is further provided with the slotted end 28^b, in which a slide block 28^c fits and forms a connection between the crank arm 33^a and the feed bar. The crank arm 33^a extends from a rock shaft 33 pivoted at 34 and adapted by its oscillation to raise and lower the feed jaw to and from the presser foot above. The rock shaft 33 is rocked by means of a suitable cam 36 and a crank arm 35 adjustably clamped upon the rock shaft. The cam 36 is secured to a shaft 37 carried in a bearing 37^a and is provided at its opposite end with a cam wheel 38 which is driven by a pinion 39 secured to the driven shaft 8, before referred to. In this manner, a continuous rotary motion is imparted to the cam wheels 38 and 36, and a rocking motion is imparted to the rock shaft 33. The feed bar 28 is pivoted at its end most distant from the rock shaft 33 to a crank arm 31 by means of a transverse pin 31^b, said crank arm being adjustably clamped near the end of a tubular rock shaft 29, the clamping construction consisting of 70 slotting the hub as at 32 and providing the clamping screw 32^a to draw the slotted parts together tightly upon the shaft, all of which construction will be better understood by reference to Figs. 2, 8 and 9. Furthermore, 75 the crank arm 31 is provided with two radial arm portions 31^a between the free ends of which the feed bar is arranged and hingedly held by the transverse pin 31^b extending through the two arms and the bar, as will 80 be fully understood by reference to Fig. 9. By this means, the oscillations of the crank arm provide a direct thrust upon the feed bar, and notwithstanding the very high speed at which the machine is driven, there 85 is a minimum of wear and lost motion. This construction of applying the power between the rock shaft 29 and the feed bar is strong and effective against undue wear, and moreover, the crank is capable of adjustment upon the rock shaft to accurately position the feed jaw. The rock shaft 29 is made tubular and of considerable length, and the ends of the tube are fitted with plugs 29^a brazed or otherwise secured therein to 90 form bearings for the pivot pins 30 at each end. This rock shaft is rocked by means of a link 42 and a second crank arm 43 which may be adjustably clamped at 44 upon the rock shaft so that it may also be adjusted circumferentially about said rock shaft when adjusting the machine. Both of the crank arms 31 and 43 are arranged relatively close together and near one end of the long rock shaft 29, so as to be near one 100 end of the end bearings and permit a reasonably direct application of power from the operating link 42 to the feed bar 28 and prevent springing of the rock shaft under high speed. Moreover, by making this rock 105 shaft hollow, the inertia of the large mass which would be present if it were made of solid steel, is overcome and the rocking motion of the shaft may be made at 3000 revolutions per minute without excessive loss of 110 power and wear upon the moving parts of the machine. While eliminating the mass in the rock shaft, it is also desirable that the two crank arms 31 and 43 should be arranged close together and near one end 115 of the end bearings to prevent the springing of the hollow shaft, heretofore referred to, especially as it is desirable to make the diameter of the shaft as small as possible consistent with sufficient strength and minimum 120 weight. The link 42 which is pivoted to the crank arm 43 at one end has its other end pivoted to a slide block 41^a adjustably clamped upon an operative arm 41 secured to a rock shaft 40. The oscillation of the 125 130

arm 41 by the rocking of the shaft 40 will produce a reciprocation of the link 42, and in that manner rock the rock shaft 29. By adjusting the slide 41^a upon the arm 41, the extent of the rocking of the shaft 29 may be adjusted, but this particular means of adjustment is old and does not form any specific part of my improvements. The rock shaft 40 is journaled in the bearing 40^a, and 10 is provided with a crank arm 45 adjustably clamped upon its end opposite to the arm 41, and said crank arm 45 engages the cam groove 38^a in the cam wheel 38 before referred to. It will thus be seen that as the 15 cam wheel 38 rotates, the cam 38^a thereof causes the rock shaft 40 to rock and by the connections to rock the tubular shaft 29, said action being at one-half the speed of the shaft 8 and therefore at one-half the 20 speed of the shaft 4 which reciprocates the needle bar. As the two cam wheels 38 and 36 are on the same shaft 37, it is manifest that the horizontal reciprocations of the feed bar 28 and its vertical reciprocations are in 25 accurately timed relation.

To compensate for any slight lost motion that might occur by long usage, and at the same time to maintain the proper contact with the cams 36 and 38^a, I prefer to 30 provide a spring 47 connected at one end to the feed bar 28 and at the other end to a bracket 46, the said spring pulling upon the feed bar 28 in an oblique direction to the two movements of said bar, whereby the 35 bar is pulled horizontally and vertically under the action of the spring, and in this manner maintains the operative mechanism always under definite tension to compensate for any slight lost motion in the reciprocating parts.

The shuttle mechanism may be of any of the usual forms and desirably of the rotary type. The shuttle mechanism is driven by the gears 53 from a shaft 52, which latter 45 is parallel to the shaft 8 and is geared thereto, this gearing being formed by a pinion 51 on the shaft 52 and a gear 50 on the shaft 8, the latter being twice the diameter of the gear 51, so that the speed of 50 the shuttle operating shaft 52 may be twice that of the shaft 8 and shaft 4 which operates the needle bar, this, however, being common to sewing machines of the "Wheeler & Wilson" type, and does not form an essential part of my improvements.

As an alternate mode of transmitting continuous rotary motion from the driving shaft 4 to the driven shaft 8 which may be used in place of the vertical shaft and 60 miter gears, I have shown in Fig. 11 a construction employing sprocket wheels on the shafts connected by a driving chain. Referring to Fig. 11, 10^a is a sprocket wheel secured to the shaft 4, and 11^a is a sprocket 65 wheel of similar diameter secured to the

shaft 8. About these sprocket wheels is an endless chain 9. In this manner both of the shafts are rotated in the same direction and at the same rates of speed, and while this may be substituted for the other manner of transmitting motion between these shafts, nevertheless I prefer, where possible, to employ the vertical shaft 9 and the miter gears 10 and 11, as hereinbefore described.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

In this application no claim is made to the mechanism for connecting the driving shaft for the needle bar in the overhanging arm with the drive shaft for shuttle and feed mechanism in the bed, nor to the mechanism for vertically reciprocating the needle or for laterally vibrating the needle, as these features will form subject matter of separate applications.

Having now described my invention, what I claim as new and desire to secure by Letters Patent, is:—

1. In a sewing machine, the combination of a cloth feed and its feed bar, a hollow rock shaft, axial pivots for supporting it at each of its ends, a crank arm adjustably clamped to the rock shaft for circumferential adjustment and providing two radial arms between which the feed bar is hinged whereby the thrust on the bar is exerted in the plane of the adjusted connection between the hollow rock shaft and crank arm, and means for rocking the hollow rock shaft.

2. In a sewing machine, the combination of a cloth feed and its feed bar, a hollow rock shaft pivoted at its ends, a crank arm clamped to the rock shaft and providing two radial arms between which the feed bar is pivoted whereby the thrust is exerted in the plane of the connection between the rock shaft and crank arm, and means for rocking the hollow shaft, said means comprising a crank adjustably clamped upon the hollow rock shaft and relatively close to the crank arm which operates the feed bar, cam means, and a link connection between the cam means and the adjustable crank.

3. In a sewing machine, the combination of a feed and feed bar, a rotary shaft for operating the shuttle or loop mechanism, a long rock shaft journaled at its ends and having an oscillating arm near one end, con-

necting means between the oscillating arm and the feed bar, whereby the latter is reciprocated, a short rock shaft having a crank arm, adjustable connections between the 5 crank arm and the long rock shaft close to its oscillating arm, whereby the angular rocking of the long rock shaft may be varied, a short cam shaft geared to the rotary shaft to revolve at a lower rate of speed and provided at each end with cam mechanism, connecting means between one of the cam mechanisms and the short rock shaft for rocking it, and means operated by the other cam mechanism for raising and lowering the feed bar, 10 all of said mechanism being located below the bed plate of the machine and in close compact relation to reduce the lengths of the connecting and coöperating parts.

4. In a sewing machine, the combination 20 of the feed and feed bar with a long hollow rock shaft widely pivoted at its ends, two crank arms each adjustably clamped about the hollow rock shaft relatively close to one end thereof, one of said crank arms being 25 hinged to the feed bar, and power devices for rocking the other of the crank arms for rocking the rock shaft.

5. In a sewing machine, the combination 30 of the feed and feed bar with a long hollow rock shaft widely pivoted at its ends, two crank arms each adjustably clamped about the hollow rock shaft relatively close to one end thereof, one of said crank arms being 35 hinged to the feed bar, and power devices for rocking the other of the crank arms for rocking the rock shaft consisting of a shaft arranged parallel to the rock shaft, an arm secured to the end of the shaft adjacent to the feed bar, a link between the arm and the 40 crank on the hollow rock shaft, a crank arm secured to the other end of the shaft carrying the arm, a cam to operate the last mentioned crank, a driven shaft, and gearing between the driven shaft and the cam, the construction being such that the link connection 45 for rocking the rock shaft shall be located relatively close to the feed bar.

6. In a sewing machine, the combination 50 of a bed, a feed and feed bar, and means for directly operating the feed bar arranged below the bed and comprising the following parts, namely, a short rock shaft arranged at one end of the feed bar and hinged thereto for reciprocating it vertically, a rotating

cam arranged close to the feed bar, an adjustable arm clamped to the short rock shaft and engaging the cam, a rotating power shaft arranged below the bed, gearing between the power shaft and the rotating cam, a long rock shaft arranged below the bed 60 at the opposite end of the feed bar, an adjustable arm clamped to the long rock shaft near one end, and to which arm the feed bar is hinged to impart horizontal motion to the feed, a crank arm adjustably clamped 65 upon the long rock shaft close to the arm which operates the feed bar, a short rock shaft arranged under the bed and relatively close to the feed and provided with an adjustable crank, a link between the adjustable 70 crank and the crank arm of the long rock shaft, and cam devices for operating the last mentioned rock shaft having the adjustable crank, said last mentioned cam devices secured to and rotating with the first 75 mentioned cam devices, whereby all of the means for imparting horizontal and vertical motion to the feed bar are arranged close to it and below the bed of the sewing machine.

7. In a sewing machine, the combination of a bed, a feed and feed bar, a long rock shaft at one end of the feed bar, a short rock shaft at the other end of the feed bar, 80 connections between the short rock shaft and the feed bar for imparting vertical motion to the bar, connections between the long rock shaft and the bar for imparting horizontal reciprocating motion thereto, a power shaft below the bed, a short cam shaft also below 85 the bed and having a cam at each end, gearing between the power shaft and the cam shaft for driving it at a lower rate of speed than the power shaft, means actuated by one of the cams for rocking the long rock 90 shaft, said means being relatively close to the feed bar, and means operated by the other of the cams for rocking the short rock shaft, all of the devices for operating 95 the feed and feed bar being arranged adjacent thereto and located under the bed of the machine.

In testimony of which invention I hereunto set my hand.

CARLIND E. MYERS.
